Patented June 14, 1960

188,230

ELECTRIC BODY MASSAGER

William N. Moxley, 3821 Don Tomaso Drive,
Los Angeles, Calif.

Filed May 5, 1959, Ser. No. 55,786

Term of patent 14 years

(Cl. D83—1)

FIG. 1.

FIG. 2.

FIG. 3.

FIG. 4.

FIG. 5.

Figure 1 is a side elevational view of an electric body massager showing my new design, the opposite side not shown being substantially the same as the side shown;

Fig. 2 is a top plan view thereof;

Fig. 3 is an end elevation as seen from the left of Fig. 1;

Fig. 4 is an end elevation as seen from the right of Fig. 1;

Fig. 5 is a bottom plan view.

I claim:

The ornamental design for an electric body massager, substantially as shown and described.
